United States Patent Office

Des. 183,585
Patented Sept. 23, 1958

183,585

HINGE

Dothan L. Shelton, Amarillo, Tex.

Application January 13, 1958, Serial No. 49,226

Term of patent 14 years

(Cl. D10—9)

Fig. 1 is a face view of a hinge, showing my new design; and

Fig. 2 is a side elevation thereof viewed at an angle parallel to the pintle of the hinge.

I claim:

The ornamental design for a hinge, substantially as shown.
